Primary Examiner — Cynthia Ramirez*Assistant Examiner* — Xavier Marti-Santos(74) *Attorney, Agent, or Firm* — Ansari Katiraei LLP;
Arman Katiraei; Sadiq Ansari(57) **CLAIM**

I claim the ornamental design for a lighted mirror, as shown and described.

DESCRIPTION

FIG. 1 is a front view of a lighted mirror, showing a first embodiment of my new design;

FIG. 2 is a back view thereof;

FIG. 3 is a right side view thereof;

FIG. 4 is a front view of a lighted mirror, showing a second embodiment of my new design;

FIG. 5 is a back view of the second embodiment;

FIG. 6 is a right side view of the second embodiment;

FIG. 7 is a front view of a lighted mirror, showing a third embodiment of my new design;

FIG. 8 is a back view of the third embodiment;

FIG. 9 is a right side view of the third embodiment;

FIG. 10 is a front view of a lighted mirror, showing a fourth embodiment of my new design;

FIG. 11 is a back view of the fourth embodiment; and,

FIG. 12 is a right side view of the fourth embodiment.

(Continued)

The broken lines in the figures are for the purpose of illustrating portions of the lighted mirror, which form no part of the claimed design.
